RAILWAY SPRING SYSTEM

Adelbert C. Wintemberg and Thomas H. Ainsworth, Drexel Hill, Pa., assignors to General Steel Castings Corporation, Granite City, Ill., a corporation of Delaware

Application October 19, 1931. Serial No. 569,719

15 Claims. (Cl. 105—195)

This invention relates to railway rolling stock and consists in a novel spring equalizing arrangement particularly adapted for six and eight wheel vehicle trucks.

5 Six wheel trucks are usually provided with either one or two spring systems on each side, each system including semi-elliptic springs resting on the journal boxes and intermediate equalizing bars pivotally supporting the truck frame. 10 These equalizing bars have been provided with single or double pivots, but it has been found that in the former case the truck is unstable and has a tendency to tilt longitudinally, while in the latter case increased stability is accompanied by 15 decreased flexibility and poor riding qualities of the truck.

In certain spring arrangements, transverse equalizers have been used which are usually hung from the ends of springs on opposite sides of the 20 truck and are pivoted to a transverse transom member of the frame intermediate the sides. However, this type of transverse equalizer requires heavy construction of the equalizing bar and transom which undesirably increase the weight 25 and cost of the truck.

The main object of the present invention is to provide improved spring equalizing means for a truck which will be more flexible than is the case where the equalizer bars have double pivotal 30 connections with the frame, and will be more stable than where the bars have single pivots.

Another object is to provide transverse equalization which will permit the use of lighter construction than has heretofore been possible.

35 These objects and others are attained in the structure illustrated in the accompanying drawings in which—

Figure 1 is a top view of a truck embodying one form of the invention.

40 Figure 2 is a vertical longitudinal section taken on the line 2—2 of Figure 1.

Figure 3 is an end view of the truck.

Figure 4 is a view corresponding with Figure 2 but illustrating a modification.

45 Figure 5 is a view similar to Figures 2 and 4 and illustrating still another modification.

Figure 6 is a detail vertical transverse section taken substantially on the line 6—6 of Figure 5.

In Figures 1 to 3, the invention is illustrated as 50 embodied in a six wheel tender truck including box section wheel pieces 1, end sills 2, transoms 3, a bolster 5 including the usual center plate 6, and pedestals 7 mounting journal boxes 8. Brackets 9 project from each end of the wheel pieces 1 for 55 mounting brake hangers 10.

Mounted on the respective journal boxes 8 are semi-elliptic springs 11, 12, and 13. Spring 13 has hangers 14 at each end which are anchored to the wheel piece by pins 15. Intermediate springs 11 and 12 is an equalizing bar 16 pivotally secured to the wheel piece by a single pivot 16a and supported at its ends by hangers 17a on the adjacent ends of the springs 11 and 12. The right hand end of spring 12 is anchored to the wheel piece by means of the hanger 17, and a hanger 18, 60 to be described hereafter, depends from the left hand end of spring 11 and projects through an opening 18a in the underside of the wheel piece. The spring arrangements on opposite sides of the truck are similar. 70

Brake hanger brackets 9 on the left end of the truck frame are provided with extensions 19 pivotally mounting bell cranks 20 which are rockable in a plane extending transversely of the truck. The lower end of the upright arm of 75 each bell crank is secured to a transverse rod 21 and the horizontal arm of each crank is operatively connected with the end of a lever 22 which is pivoted to the adjacent pedestal 7 by a pin 23 and which is supported by a gib 24 80 located near the lower extremity of hanger 18. Opening 25, receiving gib 24, is large enough to provide for varying the size of gib to adjust the spring system.

The truck frame is supported on three separately anchored spring systems, i. e., the single springs on each side of the right end of the truck and the transversely equalized system. The levers 22 are for the purpose of spacing the bell crank and transverse rod from the brake rigging. These levers could be eliminated and the horizontal arms of the bell crank supported directly from hangers 18 without affecting the operation of the spring system. 85

Figure 4 illustrates a modified form of the invention as applied to an eight wheel truck. The left hand portion of the spring system on each side of the truck, including springs 26 and 27, equalizers 28, and the transverse connecting elements, is the same as in Figure 2. Springs 29 90 and 30, mounted on the right hand pair of journal boxes, (not shown) carry hangers 31 at their adjacent ends which support an equalizer 32 having a single pivotal connection with the wheel piece. The inner end of spring 29 is anchored 105 to the frame through a hanger 33 and the outer end of spring 30 mounts a hanger 34 which depends through an opening 35 in the underside of the wheel piece and carries a spring seat 36 and coiled spring 37 seated against the under- 110

side of the wheel piece. In this modification, as in the form just described, the spring arrangements on each side of the truck are preferably identical.

5 In Figure 5, a single spring system is provided on each side of the truck. The outer semi-elliptic springs 38 and 41 are anchored to the wheel piece through hangers 42 and coiled springs 43 seating against the wheel piece. The adjacent 10 ends of each pair of springs 38 and 39 and 40 and 41 carry hangers 44 and equalizers 45, each having double pivotal connections 46 with the truck frame.

The inner ends of springs 39 and 40 mount 15 hangers 47 and a longitudinal bar 48, the latter being pinned at its center to an upright yoke 49 carried on the outer end of the horizontal arm of a bell crank 51 pivoted to a bracket 50 projecting inwardly from the wheel piece and having 20 its vertical arm connected to a corresponding bell crank on the opposite side of the truck by means of a rod 52 extending beneath bolster 53. This mechanism serves to equalize the spring systems on each side of the truck and tends to increase 25 the flexibility of the truck.

In this form, as in the forms previously described, the transverse bar receives only tensional forces and consequently may be of lighter construction than where the transverse equalizer is pivoted at the center to a transom member. Moreover, the usual comparatively heavy transom member necessary with the transverse equalizing lever is eliminated and the space provided for brake rigging is accordingly increased. In 30 all of the forms the truck is more stable than in previous trucks where all the equalizing bars are provided with single pivots and is more flexible than where the equalizers have double pivoted connection with the frame.

40 When the structure of Figures 2 and 4 is applied to a tender truck, the transverse equalizer is preferably located at the inner end of the truck frame in order to clear the draft pocket and draft gear on the tender underframe.

45 The invention may be applied to six or eight wheel trucks mounting a separate vehicle underframe or may be embodied in a structure in which the wheels are journaled in the vehicle underframe which then corresponds to the usual truck frame. Obviously, other details of the invention may be modified without departing from the spirit thereof and the exclusive use of all 50 such modifications as come within the scope of the appended claims is contemplated.

55 What is claimed is:

1. In a railway truck, spaced side frames, supporting leaf springs therefor, hangers depending from said springs, certain of said hangers having supporting connections to said frames, and transverse spring equalizing means comprising a bell crank pivoted to each of said frames and rockable transversely of the truck, oppositely disposed arms of said cranks being operated by others of said hangers, and a transverse rod connecting the other arms of said cranks.

2. In a railway truck, spaced side frames, supporting leaf springs on each of said frames, hangers depending from the ends of said springs, at least one of said hangers on each side of said truck having a supporting connection to said frame, and transverse equalizing means cooperating with other hangers on each side of the truck and comprising a bell crank pivoted to each of said side frames and rockable transversely of the truck, oppositely disposed arms of said cranks

being connected to the others of said hangers, and a transverse tension rod connecting the other arms of said cranks.

3. In a railway truck, a frame, supporting springs on each side thereof, hangers depending from said springs, and transverse equalizing means comprising bell cranks pivoted to said frame and rockable transversely of the truck, levers pivoted on said frame and swingable in a plane extending longitudinally of the truck, said levers operatively engaging oppositely disposed arms of said cranks and being engaged by said hangers, and a transverse rod connecting the other arms of said cranks.

4. In a railway truck, a frame, supporting springs on each side thereof, hangers depending from said springs, at least one of said hangers on each side of said truck having a supporting connection to said frame, a gib detachably mounted near the lower extremity of another of said hangers on each side, a lever on each side of the truck pivoted at one end to said frame and supported intermediate its ends by said gib, and transverse equalizing means comprising bell cranks pivoted to said frame and rockable transversely thereof with one arm operatively engaging the other end of said lever, and a transverse rod connecting the other arm to said cranks.

5. In a railway truck, a frame, supporting springs on each side thereof, hangers depending from said springs, and transverse equalizing means comprising bell cranks pivoted to said frame and rockable transversely of the truck, levers pivoted at their inner ends to said frame and swingable in a plane extending longitudinally of the truck, said levers at their outer ends operatively engaging oppositely disposed arms of said cranks and being operatively engaged between said ends by said hangers.

6. In a railway truck, spaced side frames, supporting spring systems therefor, each including longitudinally spaced leaf springs, an equalizer pivoted to each of said frames between said springs and supported at its ends therefrom, and hangers depending from the outer ends of said springs, and means equalizing forces on said systems comprising a bell crank pivoted to each of said frames and rockable transversely of the truck, oppositely disposed arms of said cranks being operated by one of said hangers on each side, and a transverse rod connecting the remaining arms of said cranks.

7. In a railway truck, a frame, supporting spring systems on each side thereof and including at least three longitudinally spaced springs, an outer spring being anchored at each end to said frame, an equalizing bar pivoted to said frame between the remaining springs and suspended at its ends therefrom, and hangers depending from the outer ends of said last mentioned springs, one of said hangers constituting a support member for said frame, and means equalizing said last mentioned springs on opposite sides and including bell cranks pivoted to said frame adjacent the outer ends of said last mentioned springs, oppositely disposed arms of each of said cranks being operated by the other of said hangers, and a transverse rod connecting the remaining arms of said cranks.

8. In a railway truck, a frame, supporting spring systems on each side thereof and each including two pairs of longitudinally disposed springs, an equalizer pivoted to said frame intermediate each of said pairs and supported at its ends therefrom, and hangers on the outer ends of each of said pairs, said hangers on one of said pairs and on

- one end of the other pair having supporting connections to said frame, and means cooperating with the remaining hanger of said other pair for equalizing said last mentioned pair with the corresponding pair on the other side of the truck, said means comprising bell cranks pivoted to said frame and rockable transversely of the truck, oppositely disposed arms of said cranks being operated by one of said last-mentioned hangers on each side of the frame, and a transverse rod connecting the other arms of said cranks. 5
9. In a railway truck, spaced side frames, a bolster between said frames, supporting spring systems for each of said frames and comprising longitudinally disposed springs, the outer ends of said springs mounting frame supporting elements, and a longitudinal bar supported at its ends from the inner ends of said springs, and means equalizing said systems and comprising bell cranks located between said frames and bolster and pivoted to said frames and rockable transversely of the truck, an upright member pivoted at one extremity to the middle portion of said longitudinal bar, oppositely disposed arms of said cranks operatively engaging the other extremity of said member, and a transverse rod below said bolster and connecting the remaining arms of said cranks. 15
10. In a railway truck, a frame, supporting spring systems on each side thereof each comprising a plurality of longitudinally disposed leaf springs, an equalizing bar pivoted to said frame between adjacent springs and supported at its ends therefrom, and a longitudinal bar suspended from one of said last mentioned springs and from a third spring, the outer springs also mounting frame supporting members, and means equalizing said systems and comprising bell cranks pivoted to said frame adjacent said bar and rockable transversely of the truck, oppositely disposed arms of said cranks being operatively connected with intermediate portions of said bars, and a transverse rod connecting the remaining arms of said cranks. 20
11. In a railway truck, a frame, supporting spring systems on each side thereof and comprising a plurality of longitudinally disposed leaf springs, an equalizing bar having double pivotal connection with said frame between adjacent springs and supported at its ends therefrom, and a longitudinal bar suspended from one of said last mentioned springs and from a third spring, the outer springs also mounting frame supporting members, and means equalizing said systems and comprising bell cranks pivoted to said frame adjacent said bar and rockable transversely of the truck, oppositely disposed arms of said cranks being operatively connected with intermediate portions of said bars, and a transverse rod connecting the remaining arms of said cranks. 25
12. In a railway truck, a frame, supporting spring systems on each side thereof and comprising two pairs of longitudinally spaced leaf springs, an equalizing bar having double pivotal connection with said frame intermediate each of said pairs and supported from adjacent ends of said springs, the outer ends of each pair being anchored to said underframe, and a longitudinal bar suspended from the inner ends of said pairs, and means equalizing said systems and comprising bell cranks pivoted to said frame adjacent said bar and rockable transversely of the truck, oppositely disposed arms of said cranks being operatively connected with intermediate portions of said bars, and a transverse rod connecting the remaining arms of said cranks. 30
13. In a railway truck, a frame, supporting spring systems on each side thereof and comprising two pairs of longitudinally spaced leaf springs, an equalizing bar having double pivotal connection with said frame intermediate each of said pairs and supported from adjacent ends of said springs, a hanger depending from the outer end of each pair, a coiled spring mounted on each hanger and engaging said frame, said hangers and springs yieldingly anchoring said outer ends to said frame, and a longitudinal bar suspended from the inner ends of said pairs, and means equalizing said systems and comprising bell cranks pivoted to said frame adjacent said bar and rockable transversely of the truck, oppositely disposed arms of said cranks being operatively connected with intermediate portions of said bars, and a transverse rod connecting the remaining arms of said cranks. 35
14. In a railway truck, spaced side frames, a supporting spring for each of said frames, hangers on said springs, one of said hangers on each side having a supporting connection with the corresponding side frame, adjustable gib connections in the other hangers, and transverse equalizing means comprising a bell crank pivoted to each of said frames, one arm of each crank being operated by one of said gib connections, and a rod connecting the other arms of said cranks. 40
15. In a railway truck, spaced side frames, supporting spring systems on each side thereof comprising a plurality of longitudinally disposed leaf springs, an equalizing bar having double pivotal connection with said frame between adjacent springs and supported at its ends therefrom, and a longitudinal bar suspended from one of said last-mentioned springs and from a third spring, the outer springs mounting frame supporting members, and transverse equalizing means co- operating with said longitudinal bars. 45
